UNITED STATES PATENT OFFICE.

WILLIAM ADOLPH KÖNEMAN, OF CUDAHY, WISCONSIN.

DRIER.

No. 896,025.

Specification of Letters Patent.

Patented Aug. 11, 1908.

Application filed September 25, 1907. Serial No. 394,472.

To all whom it may concern:

Be it known that I, WILLIAM ADOLPH KÖNEMAN, a citizen of the United States, residing at Cudahy, in the county of Milwaukee and State of Wisconsin, have invented a new and useful Improvement in Driers, of which the following is a specification.

The object of my invention is to provide a novel construction of rotary drier which shall render it peculiarly effective in drying rubber which has been reclaimed from rubber-waste by grinding the material to a finely divided condition and then boiling it in a suitable chemical solution to dissolve the fiber and effect devulcanization. The rubber so recovered requires to be thoroughly washed in water to remove the chemical adhering to it and cleanse it of impurities; and after it has been thus washed it must be carefully and thoroughly dried preparatory to making it up into stock to be sheeted and manufactured into rubber goods.

My improved drier is illustrated in the accompanying drawings, in which

25 Figure 1 is an end-elevation of the machine; Fig. 2, a vertical section on line 2 of Fig. 1, and Fig. 3, a transverse section on line 3 of Fig. 2.

A sheet-metal drum 7 is provided centrally 30 of its heads, about openings 8 and 9 therein, with tubular trunnions 10 and 11 at which it is journaled in horizontal position in end-frames 12 and 13. With a coupling 14 on the outer end of the trunnion 12 is connected a 35 pipe 15 having a lateral branch 16 for connection with a hot-air pipe 17 in which is interposed a fan-blower (not shown) of any suitable construction. Between the head-openings 8 and 9 there extends longitudinally 40 through the center of the drum a tubular core 19 numerously perforated throughout its wall, and this tube is preferably wrapped with a layer of porous cloth 20. The wall of the drum is formed with a plurality of openings 45 21, shown in rectangular shape, each being provided with an open-work covering, which may be a screen, but I prefer to use for the purpose a strip of canvas-cloth 22; and it fits against the flanged margin of the 50 opening upon which it is fastened by a spider-like plate 23 removably fastened to the flange.

A steam-coil 24 enters the drum through the trunnion 10 at the stuffing-box on its outer end and passes out through the opposite 55 trunnion and stuffing-box on its outer end, being coupled by return-bends outside and

inside the drum to extend back and forth within it near and about its interior wall, on which, at intervals between coils, are provided to extend lengthwise of the drum, ribs 60 25, shown of inverted-V shape in cross-section, forming stirrers for the material undergoing the drying treatment.

To operate the drier, it is charged with the damp rubber through a manhole 26 in the 65 drum, which is then continuously rotated through the medium of a gear 27 about one end engaged by a pinion 28 on a suitably-journalled drum-shaft 29. During the rotation of the drum steam is coured 70 through the piping 24 for heating the material to evaporate its moisture, the action of the steam being supplemented by that of hot, dry air forced by the fan through the pipe 15, the moisture-laden air escaping 75 through the porously-covered openings 21. By directing the hot-air supply into the perforated tubular core 19 it is distributed uniformly from the longitudinal center of the drum throughout its interior with the advantage 80 of avoiding stratification of the air-currents, to which and the heat from the steam-coil the material is thoroughly subjected by the tumbling or stirring action of the ribs 25, which serves to expose all the 85 particles of the material to the heat. The material, when thoroughly dried, is discharged through the manhole 26 on uncovering it and arresting the rotation of the drum to bring the manhole undermost. 90

The openings 21 require to be uncovered periodically to cleanse their perforated coverings or replace them with clean ones, since the coverings become clogged in time with the material; and the covering 20 on 95 the core 19, which prevents the material from entering the latter through its perforations, also becomes clogged in time and requires renewal.

What I claim as new, and desire to secure 100 by Letters Patent, is—

1. In a rotary drier, the combination of a rotatably-supported drum having a plurality of openings in its circumferential wall provided with porous coverings, said drum forming a single compartment for the material to be dried, a steam-coil in position in the drum to be exposed to contact with said material, and a perforated hot-air pipe in the drum. 105

2. In a rotary drier, the combination of a rotatably-supported drum having a plurality of openings in its circumferential wall 110

provided with porous coverings, said drum forming a single compartment for the material to be dried, a steam-coil extending in the drum about its longitudinal center and exposed therein to contact with said material, and a perforated hot-air pipe extending through the drum axially thereof.

3. In a rotary drier, the combination of a rotatably-supported drum having a plurality of openings in its circumferential wall provided with porous coverings, said drum forming a single compartment for the material to be dried, a steam-coil extending lengthwise through the drum about its longitudinal center and exposed therein to contact with said material, a perforated hot-air pipe extending through the drum axially thereof, and ribs at intervals about the inner wall-surface of the drum.
4. In a rotary drier, the combination of a horizontally-supported drum forming a single compartment for the material to be dried having tubular end-trunnions communicating with it through its heads, with a plurality of openings about the drum-wall provided with porous coverings, a steam-coil in the drum with its terminals passing through said trunnions, said coil being exposed in the drum to contact with said material, a hot-air inlet-pipe connected with one trunnion, a perforated hot-air pipe extending axially in the drum between its heads, stirrer-ribs at intervals about the inner wall-surface of the drum, and means for rotating the drum.

contact with said material, a hot-air inlet-pipe connected with one trunnion, a perforated hot-air pipe extending axially in the drum between its heads, and means for rotating the drum.

5. A rotary drier comprising, in combination, a horizontally-supported drum having tubular end-trunnions communicating with it through its heads, with a plurality of openings about the drum-wall provided with removably-fastened porous coverings, said drum forming a single compartment for the material to be dried, a steam-coil extending lengthwise through the drum about its longitudinal center with the terminals of the coil passing through said trunnions, said coil being exposed in the drum to contact with said material, a hot-air inlet-pipe connected with one trunnion, a perforated hot-air pipe extending axially in the drum between its heads, stirrer-ribs at intervals about the inner wall-surface of the drum, and means for rotating the drum.

WILLIAM ADOLPH KÖNEMAN.

In presence of—
RALPH SCHAEFER.
W. T. JONES.
